UNITED STATES PATENT OFFICE.

HENRY W. O'DOWD, OF JERSEY CITY, NEW JERSEY, ASSIGNOR TO STANDARD GAS EQUIPMENT CORPORATION, A CORPORATION OF MARYLAND.

GAS STOVE.

Application filed April 9, 1925. Serial No. 21,742.

This invention relates to thermostatically operated heat regulating or controlling devices, and has reference more particularly to devices of this kind, suitable for use in connection with ovens of gas stoves.

The general objects of the invention are to provide a device which is of simple construction and involves a minimum of parts; which is highly sensitive in action and capable of responding promptly to slight changes in temperature; which is positive and uniform in operation; which may be readily and conveniently adjusted to vary the degree of the controlled temperature; and the location of which with reference to the oven is such as to insure a more uniform temperature therein.

With these and other objects in view, the invention consists of the improved arrangement and construction of parts illustrated in the accompanying drawings, and described in detail in the specification to follow.

In the accompanying drawings:

Fig. 1 is a plan view of a portion of a gas stove having the invention applied thereto, a part of the oven being broken away to show the interior thereof.

Fig. 2 is a side elevation of the same as viewed from the right in Fig. 1.

Fig. 3 is a vertical longitudinal section on an enlarged scale through the thermostatic controlling device and adjacent parts, the section being taken on the line 3—3 of Fig. 1.

Fig. 4 is a cross sectional elevation of the same on the line 4—4 of Fig. 3.

Fig. 5 is a similar view on the line 5—5 of Fig. 3.

Fig. 6 is a similar view on the line 6—6 of Fig. 3.

Fig. 7 is a plan view of the adjusting dial wheel of the thermostatic device and adjacent valve chamber.

Referring to the drawings:

The gas stove illustrated is of the so-called "cabinet type" wherein the oven 1 is arranged to one side of and above a cooking top 2, which latter is heated by burners (not shown) supplied with gas from a front supply pipe or manifold 3. The oven is heated by a burner or burners (not shown) supplied with gas from a branch gas supply pipe 3^a extending at the side of the oven, the

supply of the gas to the oven burner being controlled by the improved thermostatic device in the manner presently to be described.

The oven structure is provided as usual with vertical side flues 4 and with a top horizontal flue 5, which latter extends between the top plate 6 of the oven and a horizontal removable flue plate 7 spaced a short distance below the top plate. The heat currents from the burner flow upwardly through the side flues as usual, and enter the oven through the communicating openings 4^a (Fig. 3) at the upper ends of the flues, whence the currents flow from the front of the oven through holes 8 in the flue plate (Fig. 1) and enter the top flue, through which they flow rearwardly and finally escape through a vent 9 leading from and communicating with the rear end of the flue.

A thermostatic device is employed for automatically regulating the supply of gas to the oven burner and for maintaining the temperature of the oven at the desired point. This device comprises essentially a thermostatic element or couple 10 and a valve 11, the said couple being supported within and extending transversely across the top flue 5 near the front but in rear of the holes 8, so as to stand in the path of the heat currents as they flow rearwardly through the flue, and the valve being disposed in the gas passage leading to the oven burner so as to regulate the flow of gas under the control of the thermostat.

The thermostatic couple may be of any suitable and appropriate form and construction, but in the preferred embodiment illustrated, it comprises an external tube 12 of a metal having a relatively high co-efficient of expansion, such as copper, and an internal rod 13 of a material having a low co-efficient of expansion, such as invar or stoic metal, or the like. The inner end of the rod is fixed to the tube as at 14, so that the movement of the tube, due to its expansion or contraction, will be transmitted positively through the rod to the valve 11, which latter is fixed to the outer end of the rod and is adjustable longitudinally thereof for the purpose presently to be described. The outer end of the thermostatic tube is fixed to a valve casing 15 which is located on the outer side of the

oven structure and is firmly fastened thereto, in the present instance by means of a hollow axial boss 16 projecting inwardly from the side of the casing and extending 5 through the side of the oven structure, and through a heat insulating packing 17 between the outer wall of the oven structure and a plate 18 at the outer side of the flue 5. The inner end of said boss terminates within 10 the flue 5 where it is screw threaded to receive a fastening nut 19 which, when screwed up on the boss, will engage the plate 18 and draw and bind the valve casing fixedly and firmly against the outer side of 15 the oven structure.

The valve casing 15 is of generally annular form and is provided at its top with a radial hollow boss 15^a constituting a gas inlet which is supplied with gas from the 20 branch supply pipe 3^a screwed into said boss. This gas inlet communicates with an elongated annular port 20 formed in the wall of a valve cylinder 21 in the interior of the casing, which port fully surrounds 25 and communicates with the interior of the cylinder. The valve 11 is in the form of a piston fitted to slide in the valve cylinder, and it is provided with a groove-like elongated annular port 22 which communicates 30 with the port 20, the degree of communication between the two ports being dependent on the position of the valve as controlled by the thermostatic couple. The valve is further formed with a number of axial ports 35 23 leading from the annular port 22 into a gas outlet in the form of a chamber 24 in the valve casing at the outer end of the valve, and this gas outlet chamber connects with the oven burner through a downwardly 40 extending pipe 25 tapped at its upper end in the lower side of the valve casing and communicating with the outlet chamber by a hole 26 formed in the valve casing, as clearly shown in Fig. 3.

From the construction described, it will be seen that the gas from the supply pipe 3^a entering the annular port 20 in the valve casing will pass into the annular port 22 in the valve and thence out through the axial ports 23 into the outlet chamber 24, whence it will flow through the hole 26 in the valve casing and enter the pipe 25 by which it will be conducted to the oven burner. It is thus seen that the gas supplied to the 50 oven burner, in passing from the inlet to the outlet, is subjected to the regulating action of the thermostatically operated valve which controls the communication between the inlet and outlet.

When the temperature in the oven is high and causes a corresponding expansion of the thermostatic tube, the latter pulls on the rod 13 and moves the valve to the left in Fig. 3, thereby shifting its annular port 22 55 relative to the annular port 20 in the valve

casing and restricting the communication between the two, and thereby reducing the supply of gas to the oven burner. When, however, the thermostatic tube contracts, due to a lower temperature in the oven, the rod 13 is pushed in the opposite direction, and the valve is correspondingly shifted to open up the ports and thereby increase the supply of gas to the burner.

It may be noted at this point that there is associated with the oven burner a pilot burner (not shown), which is supplied with gas (when the oven is in use) by means of a feed pipe 27 tapped at its upper end in the underside of the valve casing and communicating with the outlet chamber 24 through a hole 28 in the valve casing.

The piston valve is screwed onto the end of the thermostatic rod, so that by turning the valve in one direction or the other it 55 may be adjusted relatively to the thermostatic couple to vary the temperature of the oven, according to the articles of food being cooked. This adjustment of the valve is effected, in the present instance, by means of an adjusting dial wheel 29 which is attached in the manner presently to be described to a stem or stud 30 projecting outwardly from a member in the form of a tapered hub 31 rotatably mounted in a corresponding bearing opening in a plug 32 screwed into a threaded hole in the outer wall of the valve casing and forming a part of said wall. The tapered hub is held gas tight in its bearing opening by a spring 33 encircling the stem 30 and bearing respectively against the outer side of the screw plug 32 and a pin 34 fixed to said stem. At its inner larger end, the hub projects a short distance beyond the inner face of the plug 100 and the projecting end is covered by a plate 35^a fastened at its outer edge to the screw plug and serving as an additional means in preventing the escape of the gas between the hub and its seat. A flattened pin or lug 110 35 extends axially inwardly from the hub and through a circular hole in the plate 35^a, and is slidably fitted in a corresponding slot 36 formed in the outer end of the piston valve, so that by turning the dial wheel, the 115 valve may be adjusted as hereinbefore described, without breaking its connection with the adjusting wheel.

The dial wheel 29 is provided on its periphery with graduations 37 which are adapted to be read in connection with a pointer 38 fixed to an upward extension or lug 39 of the valve casing, by means of a fastening screw 40. The dial wheel is attached to the 120 stem 30 in such manner as to admit of the adjustment of the wheel circumferentially relatively to the stem in the direction of spacing of the graduations, and this for the purpose of enabling the parts to be set in their proper relative position during as- 125 130

semblage, to meet the varying conditions encountered in practice with respect to the different thermal values and the different pressures which the gas possesses in different localities. In the present instance, this adjustment is effected by means of a toothed washer or disk 41 formed with a central slot receiving a squared stud 42 projecting from the outer extremity of the stem 30 so that 5 when the washer is turned it will impart a turning movement to the stem and the parts connected therewith. The inner face of the dial wheel is recessed to receive the washer, and the peripheral wall of the recess is 10 formed with teeth 43 adapted to engage between the teeth on the washer and thereby interlock the wheel with the washer, the wheel being held in place, with the two sets of teeth detachably interlocked, by means 15 of a screw stud 44 which extends through a hole 45 in the wheel and is screwed into the outer end of the stud 42, the head of the screw bearing against the outer face of the wheel. By this method of mounting the 20 dial wheel, it can be adjusted circumferentially in the direction of the spacing of the graduations relative to the stem operated thereby, by first loosening the screw stud sufficiently to disengage the teeth, then shifting the head around to the desired position, 25 and again engaging the teeth and screwing up the stud to maintain the parts in their adjusted position. By such adjustment of the dial wheel, the graduations on the wheel 30 may be caused when positioned opposite the pointer 38, to indicate the actual temperature required under any given conditions.

The dial wheel is limited in its movement to a single rotation through 360° by means 40 of a stop lug 45^a projecting outwardly from the outer side of the valve casing in position to be engaged by a lug 46 extending inwardly from the inner side of the wheel near its outer edge, the adjustment of the 45 valve between its two extremes on the thermostatic rod being effected by the motion of the dial wheel within a complete rotation of the same.

The advantages of the foregoing arrangement of the parts will now be clear. Due 50 to its direct connection to the thermostatic couple, the valve 11 is highly sensitive in action and responds instantly to temperature changes, there being no springs, or other 55 articulated parts between the valve and the thermostatic couple so characteristic of other constructions. Furthermore, owing to the comparatively large area of the annular ports 20 and 22, the valve, although directly 60 connected to the thermostatic couple, insures an adequate and uniform supply of gas to the oven burner under all conditions of use.

The location of the thermostatic couple 65 in the top flue 5 in the manner previously described is very important and advanta-

geous, in that the couple is not exposed to the heat currents until after they have circulated through the oven and escaped therefrom through the vent holes 8, so that the action of the valve 11 will conform more 70 reliably and accurately to the general temperature prevailing with the oven. In certain types of thermostatic installations, the thermostatic couple has been located in the oven at a point where it was exposed to heat 75 currents having a temperature not truly representative of that obtaining generally throughout the oven. For instance, the thermostatic couple has been located at or closely adjacent the point in the oven where 80 the heat currents enter from the flue receiving said currents directly from the burner. Under such conditions, the thermostatic couple is influenced and operated by a degree of heat much higher than that obtaining generally throughout the oven, with the result that by the action of the thermostatic device the flow of gas is reduced before the oven has attained the particular 85 degree of temperature desired. By the location of the thermostatic couple in accordance with the invention, the oven will attain the desired temperature before the heat currents begin to influence the thermostatic couple. It will be appreciated therefore that the 90 device will operate with greater reliability and accuracy in maintaining the desired temperature than if it were subjected to a degree of heat not representative of that prevailing generally in the oven. A further 95 advantage results from the location of the thermostatic couple in the top flue, in that the flue plate 7 may be removed for the purpose of cleansing the same, or for renewal 100 or repairs, without first having to dismount or disconnect the thermostatic device, it being understood that in gas stoves of this type, the flue plates are for sanitary and other reasons, customarily made removable at will from the oven or stove structure.

As shown in Fig. 3 the gas is allowed to flow from the inlet chamber 20 to the outlet chamber through a by-pass opening 47 formed in the valve casing, which is controlled by a throttling screw 48, see Fig. 5, 115 the purpose being to insure that the oven burner, as well as the pilot burner, are supplied with a limited amount of gas continuously and independently of that controlled by the thermostatic valve, and this in order 120 to prevent the supply of gas from being cut off entirely from the burners by the action of the valve.

Wherever in the specification and claims 125 a port is mentioned in describing the ports 20 and 22, it is intended that the expression include a slot-like continuous port, as shown, or a port made up of a series of individual holes or openings related to each other so as to conjointly form in effect an 130

elongated or extended port, and to include also a port otherwise specifically formed to function similar to the port shown.

In the foregoing description and accompanying drawings, the invention has been set forth in the particular detailed forms which it is preferred to adopt, but it will be manifest that the details may be variously changed and modified without departing from the spirit of the invention. It should be understood, therefore, that the invention is not limited to any particular form or construction of the parts except in so far as such limitations are specified in the claims.

Having thus described my invention, what I claim is:

1. In a gas stove, the combination of a heating chamber adapted to be heated by a gas burner and having an outlet for the escape of the heat currents, means for supplying gas to the burner, a thermostatic element located outside the heating chamber but in the path of the heat currents flowing therefrom and in position to be acted on by said currents immediately upon their leaving the heating chamber, and means operated by said thermostatic element for controlling the supply of gas to the burner.
2. In a gas stove, the combination of a heating chamber adapted to be heated by a gas burner, means for supplying gas to the burner, a flue at the top of the chamber extending from front to rear of the same communicating at its front with the interior of the chamber at its front and having a discharge opening at the rear, whereby the heat currents from the chamber will enter the front of the flue and flow rearwardly and find their escape, a thermostatic element situated in said flue at its front in rear of the point where it communicates with the heating chamber, and means operated by said thermostatic element for controlling the supply of gas to the burner.
3. In a gas stove, the combination of an oven structure formed with a top plate and

provided with an interior chamber adapted to be heated by a gas burner, means for supplying the burner with gas, a flue plate detachably mounted in said structure below the top plate and forming in connection therewith a top flue adapted to receive the heat currents flowing from the oven chamber, a thermostatic element located in said flue, and means operated by said thermostatic element for controlling the supply of gas to the burner.

4. In a gas stove, the combination of a casing, a horizontal flue plate detachably mounted in said casing and dividing the interior thereof into a lower heating chamber and an upper flue communicating with said chamber, the said heating chamber being adapted to be heated by a gas burner, and the said flue being adapted to receive the heat currents flowing from the heating chamber, means for supplying gas to the burner, a thermostatic element located in the flue, and means operated by the thermostatic element for controlling the supply of gas to the flue.

5. In a gas stove, the combination of a heating chamber, a gas burner for heating the same, upright flues at the sides of the chamber discharging at their upper ends into the top of the heating chamber and adapted at their lower ends to receive the heating gases from the burner, a horizontal flue plate in the upper portion of the heating chamber forming a flue thereover extending from front to rear, said plate being formed at its front with openings for the entrance of the heating gases into the front end of the flue and said flue having at its rear end an outlet opening, and a thermostat situated in the front portion of the flue immediately in rear of the openings in the flue plate and adapted to control the supply of gas to the burner.

In testimony whereof I have affixed my signature hereto.

HENRY W. O'DOWD.
